US00D353310S

United States Patent [19]

Izumisawa

[11] Patent Number: Des. 353,310

[45] Date of Patent: ** Dec. 13, 1994

[54] DUAL ACTION SANDER

[75] Inventor: Nobuyuki Izumisawa, Tokyo, Japan

[73] Assignee: Shinano, Inc., Japan

[**] Term: 14 Years

[21] Appl. No.: 7,905

[22] Filed: May 4, 1993

[52] U.S. Cl. D8/62

[58] Field of Search ..... D8/62, 61; 51/170 R,
51/170 T, 170 TL, 170 EB, 170 MT; D15/139
